UNITED STATES PATENT OFFICE.

ENOCH COX, OF MALTA BEND, MISSOURI.

DESIGN FOR A HINGE.

SPECIFICATION forming part of Design No. 30,895, dated May 30, 1899.

Application filed March 31, 1899. Serial No. 711,285. Term of patent 3½ years.

To all whom it may concern:

Be it known that I, ENOCH COX, a citizen of the United States, residing at Malta Bend, in the county of Saline and State of Missouri, have invented and produced a new and original Design for a Hinge; and I do declare the following to be a full, clear, and exact description of the same, reference being had to the accompanying drawings, forming a part thereof.

10 Figure 1 is a view of the face of my hinge. Fig. 2 is a sectional view of my hinge.

Similar letters of reference refer to similar parts throughout both views.

15 Referring to the drawings, B represents the parallelogram half of the hinge.

A represents the scalloped portion of the hinge.

CCC represent countersunk screw-holes on

the part A, and D D D represent countersunk screw-holes on the part B.

20 The leading feature of my design is in the configuration as shown, one half of the hinge being a parallelogram and the other half being scalloped or notched, as shown, the edges of the part being beveled and designed to present a finished appearance.

What I claim, and desire to secure by Letters Patent, is—

25 The design for a hinge, as herein shown and described.

30 In testimony whereof I affix my signature in presence of two witnesses.

ENOCH COX.
